UNITED STATES PATENT OFFICE.

ADAM McCRAKEN, OF LONDON, ENGLAND.

REAMER.

Application filed September 1, 1921. Serial No. 497,654.

To all whom it may concern:

Be it known that I, ADAM McCRAKEN, a subject of the King of Great Britain and Ireland, and a resident of London, England, have invented a certain new and useful Improvement in Reamers, of which the following is a specification.

This invention relates to the enlarging of the lower end of holes or bores drilled in rocks, surface quarrying and underground mining, for the reception therein of blasting charges, and the object of the present invention is the provision of a rotary tool, as hereinafter set forth for effecting such enlargement of the holes or bores, after the latter have been made by the ordinary drill heretofore in use.

A tool in accordance with the invention consists of a steel bar with a longitudinal 20 and centrally disposed bore therethrough, said bore being tapped at its upper end to receive the threaded part of a feed rod, and at its lower end enlarged for the reception therein of a slidable, but non-rotatable, 25 cylindrical and fork-shaped block.

The feed rod is, at its lower end, rotatably and detachably secured to the base part of the cylindrical block aforesaid, and in the fork of said block a pair of cutters are 30 slidably mounted, said cutters being provided with lugs arranged at an angle of 60 degrees or thereabouts, slidably fitting in grooves in the faces of the fork, the grooves running at the same angle as the 35 lugs, the arrangement being such that on forcing down the block, by screwing down the feed rod, said cutters are gradually forced outwards through radially disposed slots formed in the wall of the enlarged part 40 of the bar, said enlargement being closed by means of a removable nipple or plug which forms a level base for the bottom of the cutters to slide on.

The invention will now be fully described 5 with reference to the accompanying drawings, in which:—

Figure 1 is a sectional elevation of the tool; and

Figure 1^a is a view showing a means for 50 connecting said tool to a prime mover.

Figure 2 is a cross-section through line 2—2 of Figure 1, the tool being shown with the cutters closed.

Figure 3 is a sectional elevation of the 55 cutter end of the tool, taken at right angles

to the view shown in Figure 1, and showing the cutters expanded; and,

Figure 3^a is a sectional plan view illustrative of the saddle pin hereinafter referred to.

Figure 4 is a sectional plan view of the cutter end of the tool, through line 4—4, Figure 3.

Similar letters of reference indicate like parts where occurring.

In carrying this invention into effect, a round bar *a*, Figure 1, of mild steel (which may be case-hardened) bored centrally the whole of its length and of a diameter and length to suit the diameter and depth of the 70 hole required, is made use of as the holder for the cutters, the upper end of which holder can be adapted to existing power appliances in the manner herein described and shown in Figure 1^a.

The upper end *a*³ of the bar *a* is of hexagonal shape, and over such hexagonal end and a portion of the cylindrical part of the bar *a* therebelow, there is fitted and secured the lower end of a skeleton-like box or cage 80 *a*⁴, said box or cage *a*⁴, which is of a length to suit requirements, being at its upper end, fixedly connected to the spindle *a*⁵ which receives rotary motion from the prime mover, said spindle *a*⁵ being raised and lowered by graduated stages when the tool is making its enlarging transverse cuts.

The bore is tapped at its upper end *a*' (see Figure 1) and a feeding rod *b* is passed through the bore to the lower end of the bar *a*. The feeding rod *b* is threaded at its upper end *b*' for engagement with the threaded end *a*' of the bar *a*, and at its lower end is connected to a mild steel cylindrical block *c* case-hardened and fitting in an enlargement 90 *a*² of the bore in the bar *a*. The wedge portions of the block *c*, which, as shown in Figure 1, is forked to receive the cutters *d* are constituted by the grooves *e* arranged at an angle of 60 degrees or thereabouts on the inside faces of the forked member *c*, and in said grooves *e* slidably fit the lugs *d*' on the cutters *d*, said lugs being arranged at the same angle as said grooves.

The length of the cylinder *c* is just sufficient to clear the face of the bottom of the bar. At the base of the cylinder *c* a suitable hole is drilled for the end of the feed rod *b* and small holes are drilled to take a saddle pin *f*—Figures 3 and 3^a—forming 110

a swivel joint between feed rod and cylinder, whilst rotation of said cylinder is prevented by means of a set screw passed into a groove formed in the exterior surface of said cylinder.

The cutters *d* are of such a size that their cutting edges are flush with the circumference of the bar *a*, when in their inoperative position, and are adapted to be expanded 10 outwards through slots in the wall of the holder bar *a* aforesaid—see particularly Figure 3. The cutters *d* overlap at their inner ends and the two slide simultaneously in 15 opposite directions. The cutting blades *d*, after each cut, are, by rotating the feed rod *b*, by means of a tommy or other tool, passed through the openings of the box or cage *a*, to engage in one or the other of the holes *b* in the head of the feed rod *b*, thus forcing 20 the cylinder *c* downwards, gradually pushed outwards, transversely of the tool, through the slots in the wall of the bar *a* until stopped by the limit of the size of the mechanism. At this stage the back edge of the 25 cutters *d* still overlap—see Figure 4.

After the first recess is cut, the bar *a* may be withdrawn to nearly the height of the plates, and the cut again made, and this 30 operation may be repeated to whatever length of countersink is required.

By rotating the screw *b* in the opposite direction the cylinder *c* is drawn upwards, and at the same time, by the grooves *a* in the faces of the fork of the cylinder being 35 engaged by the lugs *d* on the cutters *d*, said cutters are gradually withdrawn until they recede within the walls of the round bar *a*—as in Figures 1 and 2—when the bar *b* can be withdrawn, and the bore can be cleaned 40 out.

A nipple or plug *g* formed with a recessed internal thread which engages an external thread on the lower end of the bar *a*, serves to strengthen said bar *a* at that part, 45 and by leaving a centre of metal in said plug *g* to approximately fit the internal bore of the bar *a* and lie flush with the bottom of the cutting blades *d*, a smooth level base is provided upon which the cutting 50 blades *d* slide. The outer end *g* of the nipple or plug *g* is prolonged to enable débris from the bore to collect, and a hole *h* is drilled in the end *g* to allow of a tommy being used for unscrewing and screwing up.

55 To withdraw the cylinder *c* and cutting

blades, the nipple or plug *g* is unscrewed, the feed rod *b* is screwed down until the cylinder *c* is entirely exposed and then with a pointed instrument the saddle pin *f* can be levered out and the cylinder taken off. 60 The rod *b* can then be taken out by unscrewing same from the bar *a*. Provision is made for the injection of water or other fluid through the feeding rod *b*, or through any suitable part of the bar *a*. Grooves *i* are machined in the bar on either side of the cutters to carry off the débris.

I claim:—

1. A rotary tool for the purpose set forth including a bar having a central longitudinal bore, the upper end of which is threaded and the lower end of which is enlarged and provided with lateral slots, a feed rod having a threaded portion screwing into said threads of the bore, a cylindrical and fork-shaped block slidably but non-rotatably mounted in said enlarged lower end of the bore and the inside faces of the forked portion of the block having grooves arranged at an angle of approximately 60 degrees, means for rotatably and detachably securing said feed rod to said cylindrical block, a pair of radially disposed cutters slidably mounted in the fork of the block, lugs on the cutters arranged at approximately an angle of 60 degrees and being slidable in said grooves, and a removable plug enclosing the enlarged end of the bar and forming a level base for the bottom edges of the cutters to slide upon. 85

2. A rotary tool for the purpose set forth including a bar having a central horizontal bore formed with threads at its upper end and the lower end thereof being enlarged and provided with lateral slots, a feed rod having a threaded portion adapted to engage with the threads of the bore, a cylindrical fork shaped block carried by the lower end of the rod and arranged in the enlarged lower end of the bore, means for detachably and rotatably securing said feed rod to said block, a plug enclosing the enlarged end of the bar, and cutters slidably interlocked with the inner faces of the fork shaped cylindrical block and bearing against 100 said plug, said cutters projecting through the lateral slots of the bar. 105

In testimony whereof I have affixed my signature hereto this 21st day of June, 1921.

ADAM McCACKEN.
